UNITED STATES PATENT OFFICE

RUDOLPH J. LANGER, OF MONTICELLO, IOWA, ASSIGNOR TO FRANKLIN EQUIPMENT CO., OF MONTICELLO, IOWA, A CORPORATION OF IOWA

FENCE POST BRACE

Application filed January 5, 1931. Serial No. 506,657.

This invention relates to fence post braces or stretcher members which may extend diagonally or horizontally between fence posts.

The object of the invention is to provide a strong rigid brace which may be made from a minimum of metal, which will be efficient for its intended purpose, attractive in appearance and economical to manufacture.

In the drawing:

10 Fig. 1 is a side elevation of two fence posts between which is a brace embodying my invention.

Fig. 2 is an enlarged longitudinal sectional view of one end of the brace.

15 Fig. 3 is an enlarged transverse section taken on the line 3—3 of Fig. 2.

Fig. 4 is a side elevation of a modified form of end for the brace.

Fig. 5 is a transverse section taken on the 20 line 5—5 of Fig. 4.

Referring to that embodiment of the invention shown in the drawing, the fence post brace is indicated as a whole at 10 and it comprises a single piece of metal bent longitudinally at two places, 11 and 12, between its longitudinal edges 13 and 14, to form a substantially flat top surface 15 and depending sides 16 and 17. The side walls 16 and 17 are slightly inclined outwardly as they extend downwardly from the edges of the top 15, then curved outwardly as indicated at 18 and 19, respectively, and then are turned inwardly at 20, 21 between the curved portions 25 and the margins 13 and 14, respectively.

In the form shown in Figs. 1 to 3 inclusive, at each end of the brace 10 the metal forming the sides is pressed toward the inner surface of the top 15 to form flat ends 22 which are bent so as to extend at an angle to the surface 15, and apertured for attachment by screw bolts 23 to the fence posts 24. As shown in Fig. 1, the member 10 is used 40 as a diagonally extending brace between two fence posts but a plurality of stretcher mem-

bers 10 may be disposed horizontally to form cross bars for a fence.

In Figs. 4 and 5 is shown a modified form of end for the member 10. Instead of having the metal crushed together to form a flat end, 50 the side walls are only pressed inwardly to a limited extent near each end of the brace 10, as indicated at 25 in Fig. 5, and the post 24 is cut away at 26 to receive the end of the brace.

Changes may be made in details of construction without departing from the scope of my invention and I do not intend to be limited to the exact form shown and described except as set forth in the appended 55 claims.

I claim:

1. A fence post brace made of a metal strip, comprising a longitudinally extending top wall and integral side walls depending 65 from the longitudinal edges of said top wall, said side walls being curved outwardly and then inwardly adjacent their lower edges to provide strengthening means extending longitudinally of the brace, and the ends of the 70 top and sides being bent into post attaching portions.

2. A fence post brace made of a metal strip, comprising a longitudinally extending top wall and integral side walls depending from 75 the longitudinal edges of said top wall, said side walls being curved transversely adjacent their lower edges, the top and sides at the ends of the brace being flattened and bent at an angle to the top to provide post attaching 80 portions.

3. A fence post brace comprising a strip of metal having a substantially flat top wall and integral depending sides, said side members 85 being slightly inclined outwardly from said top, then curved outwardly adjacent the lower edges and the lower edges turned slightly inwardly toward each other to provide edge strengthening means extending longi- 90

tudinally of the brace, and post attaching means at the ends of the brace.

4. A fence post brace comprising a strip of metal having a substantially flat top wall and integral depending sides, said side members being slightly inclined outwardly from said top, then curved and the lower edges turned slightly inwardly toward each other, and flattened end members extending at an obtuse angle to the plane of the top surface of the brace.

In testimony, that I claim the foregoing as my invention, I affix my signature, this 31st day of December, 1930.

RUDOLPH J. LANGER.
